UNITED STATES PATENT OFFICE

By ALEXANDER M. MARION, OF PITTSBURGH, AND EMIL C. GERRY, OF CANONSBURG, PENNSYLVANIA

RETREATING LONGWALL FACE MINING MACHINE

Application filed March 7, 1927, Serial No. 173,331.

The invention relates to new and useful improvements in mining machines, and more particularly to a continuous cutting, shearing, breaking down and loading machine for long wall system of coal mining.

An object of the invention is to provide a mining machine of the above type having a body portion which is adapted to be propelled with a forwardly projecting horizontal frame extending across the front end of the body portion and supporting a traveling cutter adapted to produce a horizontal kerf into which the frame is moved, and also supporting a conveyor traveling at right angles to the longitudinal axis of the body for receiving the undercut material and delivering the same at one side of said body portion.

A further object of the invention is to provide a machine of the above type wherein the frame carrying the conveyor is provided with a supporting plate over which the conveyor travels, which supporting plate aids the conveyor in the supporting of the material.

A still further object of the invention is to provide a machine of the above type wherein the traveling cutter is in the form of an endless traveling cutter bar, and wherein said cutter bar is operated by a driving device mounted on the body portion of the machine.

A still further object of the invention is to provide a machine of the above type with a vertical frame carrying a traveling cutter bar for cutting a vertical kerf adjacent one end of the horizontal frame, said vertical frame being mounted on the body of the machine and capable of being swung in a vertical direction for shifting the position of the vertical cutting bar.

A still further object of the invention is to provide a mechanically actuating mechanism for shifting said vertical frame.

A still further object of the invention is to provide said vertical frame with tension pads adapted to bear against the body of the machine for holding said vertical frame in tension and preventing undue vibration thereof during the operation of the vertical cutter bar.

A still further object of the invention is

to provide said vertical frame with pressure blocks which are adapted to be shifted by manually controlled mechanically actuating means so that said pressure blocks may be placed in set position to bear against the side wall of the vertical kerf to guide and steady the vertical frame in its forward travel, and which also may be operated to cause pressure to be applied against the vertical wall of the undercut material for breaking down said material.

A still further object of the invention is to provide a machine of the above type wherein the body portion carries a vertical standard capable of being adjusted as to height, and at the upper end of which is a projecting bracket carrying a recess cutter for cutting a recess in the side wall of the material adjacent the roof thereof in which a supporting roof beam can be placed.

These and other objects will in part be obvious and will in part be hereinafter more fully disclosed.

In the drawings which show by way of illustration one embodiment of the invention—

Fig. 1 is a view partly in section and partly in plan with portions thereof broken away to show the structure of the machine;

Fig. 2 is a view partly in section and partly in side elevation of the machine;

Fig. 3 is a sectional view transversely of the machine and centrally of the forwardly projecting horizontal frame;

operated cutting bar, and showing a modified form of actuating mechanism for the pressure blocks;

Fig. 10 is an enlarged sectional view showing the cutter for forming the recess for the roof beam;

Fig. 11 is a sectional view of the transmission mechanism for controlling the caterpillars which support and operate the mining machine; and

Fig. 12 is a sectional view through one of the tension pads carried by the frame which supports the vertical cutter.

The invention is directed broadly to a mining machine capable of continuously cutting, shearing, breaking down and loading the material solely by the use of traveling cutter bars and pressure blocks without the use of explosives. The machine is particularly adapted for use in connection with the long wall system of coal mining. The machine consists of a body portion mounted on tractors which are independently driven and controlled, so that the machine may be propelled either in a forward direction or rearwardly and guided in its movements. At the forward end of the body portion and extending all the way across the same is a horizontally projecting frame. Mounted on this frame is a travelling cutter bar which travels across the front end of the frame and cuts a kerf in the material into which the frame may be moved by the forward movement of the body portion of the machine. This travelling cutter bar may be of any well known endless type. It travels across the front side of the frame where the cutting is performed, then underneath the frame which is elevated for this purpose, and then across the front end of the body portion of the machine where it engages actuating mechanism therefor. The frame is attached to the body by devices which enable shims or other means to be used for shifting the supported position of the frame, and thus taking up the slack in the endless cutter bar. There is a connection between the frame and the body of the machine which permits this adjustment in a direction longitudinally of the frame, but which prevents any movement of the frame on the body thereof laterally of the body. Mounted on the frame are supporting plates which underlie the undercut material, and traveling across these plates are two conveyors. The conveyors are located side by side, and are formed of a series of connected links. These conveyors receive the material which is undercut when it is broken down. The plates support the conveyors, and the conveyors travel in a direction transversely of the longitudinal axis of the body portion of the machine, and thus receive and dump the material at one side of the machine. Mounted on the body portion of the machine is a vertically swinging frame

which is located at one end of the horizontal frame. This vertically swinging frame is provided with an endless vertical cutter bar which cuts a vertical kerf into which the vertical frame is moved when the machine moves forward. The vertical frame is pivoted to the body portion of the machine, and tension pads are provided which bear against the body portion to prevent excessive vibration in the vertical frame. Pressure blocks are also provided on said vertical frame which may be shifted and placed in set positions so as to bear against the vertical wall of the material in the vertical kerf. These pressure blocks, when properly set, serve to guide the vertical frame in its forward travel. These pressure blocks may also be moved by actuating wedges for exerting a pressure against the material for breaking it down. The vertical frame is capable of being shifted, as noted, and this is accomplished by manually controlled mechanically actuating mechanism. Also mounted on the body of the machine is a vertical standard which carries a laterally projecting bracket at its upper end. The standard is capable of adjustment for varying the height thereof. At the outer end of this bracket is a cutter for cutting a recess in the vertical wall which is adapted to receive a roof beam. This recess is cut right up close to the roof, so that the beam when inserted in the recess, will directly engage and support the roof.

The invention will possibly be better understood by detail reference to the drawings.

Machine body structure

The machine includes a body portion which is provided with means for propelling the same in a forward direction or rearwardly, and at different speeds. This body portion includes a main frame structure 1 which is mounted on caterpillar tractors 2, 2, one at each side of the machine. These caterpillar tractors are of the usual construction and will not need detail description. They are operated by a motor M mounted on the frame of the machine. This motor carries a gear 3 which meshes with a gear 4 on a shaft 5. which shaft is journaled in suitable bearings carried by the frame. On the hub of the gear 4 is a second gear 6, and this second gear meshes with a gear 7 on a shaft 8. The shaft 8 carries two gears 9 and 10. The gears 9 and 10 are connected to the transmission mechanism for the tractors by a train of gears so proportioned that the gear 10 will give a slow propelling movement to the tractors, while the gear 9 will give a faster propelling movement to the tractors. Otherwise, these trains of mechanism are similar. The gears 9 and 10 are worm gears, and the gear 9 meshes with a worm gear 11 on a shaft 12. This shaft 12 carries a worm gear 13 which meshes with a worm gear 16 freely mounted

on a sleeve 15. The other train of mechanism meshes with a worm gear 14 likewise freely mounted on the sleeve 15. This sleeve 15 is carried by a shaft 17. Parallel to the shaft 17 is a second shaft 18. (See Fig. 11.) A gear 19 is formed as a part of the sleeve 15, and the sleeve 15 is keyed to the shaft 17. This gear 19 meshes with a gear 20 which is keyed to the shaft 18. A clutch collar 21 is keyed to the sleeve 15, and is adapted to be connected to the worm gear 14, and when so connected, then the two shafts 17 and 18 will be driven from the motor, the two shafts, however, turning in opposite directions. Also on the sleeve 15 is a clutch collar 22, and this is adapted to be shifted so as to connect the worm gear 16 with the sleeve 15, and when so connected, then the two shafts 17 and 18 will be driven, but at different speeds, as noted above.

One of the tractors is driven by a sprocket connection with a sprocket wheel 23 mounted on a stub shaft 24. This stub shaft 24 carries a gear 25 which meshes with gears 26 and 27 freely mounted on the shafts 17 and 18, respectively. A clutch collar 28 is used for connecting the shaft 17 to the gear 26, and when so connected, then the tractor at one side of the machine is driven in a forward direction and at a relatively slow speed. There is a clutch collar 29 which is adapted to connect the shaft 18 with the gear 27, and when so connected, then the tractor will be driven from the shaft 18 in a rearward direction.

At the opposite side of the machine there is a sprocket wheel 30 for driving the other tractor. This sprocket wheel 30 is connected to a gear 31 which meshes with gears 32 and 33, and these gears 32 and 33 are controlled, respectively, by clutch collars 34 and 35. The clutch collars are shifted by means of hand-actuated members 36, 36. The details as to the control of these clutch collars is not thought necessary to an understanding of the present invention. It will be noted, however, that by these control levers and the transmission mechanism described above, the machine can be propelled from the motor mounted on the body thereof, either in a forward direction or in a rearward direction. It can be propelled at two different speeds, and the tractors can be independently controlled for turning or guiding the machine.

55 *Horizontal kerf cutting mechanism.*

At the forward end of the machine there is a horizontal frame 38. This frame extends all the way across the front end of the machine, from one side thereof to the other, and projects to the left of the machine as viewed in Fig. 1. The frame has a vertically extending supporting member 39 and a horizontally extending member 40. The vertical member 43 is attached to the front end of the machine

by suitable bolts 41^a, 41^b. This vertical member has a rearwardly projecting fin 41 which is adapted to engage in a recess 42 in the frame (see Fig. 1). Said fin freely engages in the recess, but is of such proportions as to prevent any lateral movement of the frame relative to the body of the machine. It permits, however, the frame to be adjusted in a direction longitudinally of the frame, and this may be done by loosening the bolts which attach the frame to the body of the machine and inserting shims or plates 43 between the frame and the body portion of the machine. The horizontal portion of the frame is provided with vertically extending ribs 44 and 45. These are strengthening ribs, and the ribs 45 also support a steel plate 46 which extends from end to end of the frame, and from one side thereof to the other.

Supported on this horizontal frame is a horizontal cutter bar which cuts a kerf in the material. This cutter bar is indicated at 47 in the drawings. It travels in a suitable guiding channel carried by a cutter bar support 48 which is a part of the frame 38. The cutter bar, as shown in Fig. 1, extends all the way across the front end of the machine. The horizontal portion of the frame is of such dimensions that it may move into the kerf cut by the horizontal cutter bar. Said cutter bar is provided with the usual cutting tools 49. The cutter bar extends along the front side of the frame 38, thence underneath the portion 40^a of the horizontal frame, thence across the front end of the machine where it engages a driving sprocket gear 50. The horizontal cutter bar then travels about the right-hand end of the frame 40, as viewed in Fig. 1, and across the front side of the frame, as noted above. The sprocket gear 50 is carried by a shaft 51 which is journaled in suitable bearings carried by the body 1 of the machine. The shaft 51 carries a worm gear 52 at its upper end, which meshes with a worm gear 53 on the shaft 54 of the motor M'. Thus it is that the motor M' operates the horizontal cutter bar. The driving mechanism for this horizontal cutter bar is carried by the main body portion of the machine, and the fin and recess connection between the frame 40 and the body portion of the machine prevents any lateral movement of the frame on the machine, due to the cutting thrusts on the cutter bar.

120 *Conveying mechanism*

The horizontal frame 40 is provided with a central projecting rib 55 which projects above and below the main portion of the frame 40. Traveling on opposite sides of this rib 55 are endless conveyors 56 and 57. These endless conveyors are similar in construction, and it will only be necessary to describe one of the conveyors. The conveyor 56 runs over the top of the horizontal frame and over the

plate 46, and travels between the rib 55 and a raised rib 58 at the inner side of the frame 40. The conveyor itself is made up of a series of connected links 59, 59. These links are all similar in construction, and each link is provided with a projection or lug 60. The links are pivoted together in the usual way. The links are joined so that the projections 60 throughout the central portion of the conveyor, as viewed in Fig. 5, project upwardly after the manner shown in Fig. 6, while the links at the sides of the conveyor, project downwardly as viewed in Fig. 5. The purpose of the downwardly projecting members is to provide lugs which cooperate with sprocket wheels for driving the conveyor, and the purpose of the upwardly projecting lugs is to insure a proper gripping contact with the material which falls on to the conveyor for conveying the material. A plate 61 is carried by the rib 55 and overlies the edge of the conveyor, while a plate 62 is carried by the rib 58 and likewise overlies the side edge of the conveyor. This endless conveyor runs over sprocket wheels carried by a shaft 63 at one end of the frame as viewed in Fig. 1, and over sprocket wheels carried by a shaft 64 at the other end of the frame. The endless conveyor 57 also runs over sprocket wheels on this shaft 64 and over sprocket wheels on a shaft 63^a at the other end of the frame. The shaft 64 is driven by a bevel gear 65 which meshes with a bevel gear 66 carried by a shaft mounted in a bracket 67. This stub shaft which carries the bevel gear 66 is driven by shaft 68 which has a universal connection with a shaft 69. The shaft 69 has a splined connection with a gear 70 and is capable of endwise movement in this gear 70. The gear 70 meshes with a gear 71 on a counter-shaft which carries a gear meshing in turn with a gear 72 on the end of the motor shaft 54. Thus it is that the motor M' operates the endless conveyors, and the shaft 64 is made capable of adjustment for taking up the slack in the endless conveyor. This is accomplished by the aid of screws 73, 73.

As shown in Fig. 3, the endless conveyor travels in a horizontal plane across the front of the machine, and it is then inclined upwardly so as to pass over the cutter bar and also to pass over a suitable conveyor at the side of the machine for receiving the material. The material being undercut by the horizontal cutter, when broken down, will drop on to these endless conveyors, and the material will be supported by the steel plates beneath the conveyors. As the conveyor belts travel over these steel plates, they will convey the material transversely to the direction of the longitudinal axis of the machine and deliver the same at one side of the machine. The cutter bar cuts a kerf which is deep enough to allow the horizontal frame with its associated conveyor to be moved into

the kerf. The tractors of the machine may be so connected to the operating motor as to gradually feed the machine forward, as the horizontal cutter bar cuts its kerf, and thus a horizontal kerf is formed, and this frame with its conveyor is gradually carried into the kerf and will receive at any time the material breaking down and convey it to one side of the machine, so as not to interfere with the forward travel of the machine.

As noted above, the machine is particularly adapted for operation in what is often referred to as a long wall system of coal mining. It will be understood, of course, that the wall is at the right of the machine, and the horizontal cutter cuts a horizontal kerf extending inwardly from the wall thereof, and as the material is broken down, it will be delivered by the conveyor to the left-hand side of the machine or into the space along-side of the previously cut long wall.

Vertical kerf cutting mechanism

The machine is also provided with a vertical kerf cutting mechanism which is located at the right of the machine.

This cuts a vertical kerf in the material back from the long wall referred to, and in effect, forms a new long wall. The vertical cutter is located at the extreme right-hand side of the machine so as to cut a kerf in the material so disposed that when the material between this vertical cutter and the outer wall is broken down, it will leave a proper space for the forward movement of the machine. It will be understood that the vertical cutter may be placed on the left-hand side of the machine, if desired. This vertical cutter consists of a supporting frame 74 which is carried by a bracket support journaled on the body portion of the machine so as to be shifted about the axis of the shaft 5. This frame 74 is provided with suitable channel bar supports 75 for the vertical cutter 76. The vertical cutter 76 is of the usual endless chain type, and runs over a sprocket wheel 77 on the shaft 5. The gear wheel 4 is freely mounted on the shaft 5 and is connected to the shaft 5 by means of a clutch collar 78 controlled by a hand lever 37. Thus it is that the motor M may be used for operating the shaft 5, and for operating the vertical cutter 76. The frame 74, as noted above, is shiftable about the axis of the shaft 5 as a center. This is accomplished by means of a segmental rack 79 which is fixed to the frame 74 and a gear 80 which meshes with said segmental rack. The gear 80 is mounted on a shaft carrying a worm gear which meshes with a worm gear 81 on a shaft 82. The shaft 82 carries a worm gear at its other end, which meshes with a worm gear 83 loosely mounted on the shaft 5. A clutch collar 84 is splined to said shaft 5 and may be connected to the gear 83 for operating the gear 80 which will

125
130

cause the frame 74 to be shifted in a vertical plane about the axis of the shaft 5 as center. The frame 74 is provided with a series of recesses 85 (see Fig. 12). Located in each recess 85 is a pressure pad 86. This pad 86 carries a limiting bolt 87 provided with a nut 88. A spring 89 bears against the inner side of the pad 86. This spring also in turn bears against a plate 90 which is secured to the frame 74 by means of bolts 91, 91. Plates or shims 92 may be placed between this plate and the frame, and thus the tension of the spring 89 on the pad is varied. These pads are so disposed that they bear against a segmental plate 93 on the frame of the machine (see Fig. 2). As indicated in this figure, there are four of these pressure pads. The purpose of these pads is to put a tension on the frame 74 so as to prevent vibrations in this frame during the operation of the vertical cutter bar. The pads bearing against the segmental plate will force the frame outwardly at this point, which is some distance from its pivotal support, and thus put the frame under tension, as stated.

The vertical frame is also provided with pressure blocks. As shown in the drawings, there are two of these pressure blocks 94 and 95. These pressure blocks are similar in construction, and are operated by similar devices. Associated with each block is a wedge 96 having an inclined face 97 and a face 98 which is parallel with the plane of the vertical cutter bar. This face 98 of the wedge 96 rests and slides on a plate 99 carried by the frame 74. The pressure block 94 has an inclined face 100 which engages the inclined face 97 on the actuating wedge. A bolt 101 is carried by the pressure block 94 and extends through a slot in the wedge 96. The head 102 of the bolt has an inclined face which engages the inner recessed face of the wedge 96. This head 102 overlies the slot and thus provides a means whereby when the wedge is moved to the right as viewed in Fig. 8, it will withdraw the block 94 so that it is flush or beneath the surface of the frame. When, however, this wedge is moved to the left as viewed in this figure, then the block is forced outwardly. The block may be moved outward a slight distance by the manipulation of the wedge, and held in such set position, if the wedge is held from movement. It may be moved out to the broken line position, indicated in Fig. 8. These pressure blocks are well out toward the end of the frame and near the cutting region of the vertical cutter bar. The purpose of the blocks is twofold. These blocks will engage the side wall of the vertical kerf as it is formed, and the machine progresses into the kerf. The blocks may be moved a sufficient distance only to serve as supporting and guiding members for the vertical frame in its forward travel and to steady it against undue vibration during the cut-

ting operation. The other purpose of these cutting blocks is to break down the undercut material. The wedges are operated by mechanism which is manually controlled, and at the proper time may be forced outwardly to the broken line position indicated in Fig. 8, and thus pressure brought to bear against the side wall of the vertical kerf to force the material so that it will break down. It is understood, of course, that in coal mining, the coal often has a grain. The pressure blocks are staggered, and thus it is that by the operation of these blocks, the pressure can be distributed over a large longitudinal area and breaking down of undercut material assured.

These wedges may be moved forward and back by any desired type of actuating mechanism. We prefer, however, to use a hydraulic mechanism for this purpose. This hydraulic mechanism is illustrated in Figures 1 and 7. To each wedge is attached a piston rod 103. This piston rod 103 is connected to a piston 104 working in a cylinder 105. There is, of course, a piston rod and cylinder for each wedge, as shown in Fig. 7, where the piston rod for one of the wedges is indicated at 103 and for the other wedge is indicated at 103^a. The piston rod 103 is associated with a cylinder 106 and the piston rod 103^a is associated with a cylinder 106^a. These pistons are operated hydraulically, and in order that this may be accomplished, a pipe 107 is connected at the outer end of the cylinder 106, and a pipe 108 is connected to the outer end of the cylinder 106^a. These pipes lead to a common pipe 109 which in turn is connected to a control casing 110. A pipe 111 is connected to the other end of the cylinder 106, while a pipe 112 is likewise connected to the other end of the cylinder 106^a. These pipes 111 and 112 are connected to a common pipe 113 which in turn is connected to the casing 110. These pipes will, of course, be of such a flexible character or provided with flexible connections so as to permit the free swinging of the cutter frame. Mounted for reciprocation in this casing 110 is a valve rod 114. Oil under pressure is supplied to the casing 110 through a port 115. The casing is provided with ports 116 and 117 which are connected with a supply reservoir. When the piston rod 114 is in the position shown in Fig. 7, the pipes 109 and 113 are cut off, or substantially so. If the valve rod 114 is raised, as viewed in this figure, that is, withdrawn from the casing, then the pipe 109 will be connected to the oil supply under pressure, and the pipe 113 will be connected to the reservoir. When this piston rod 114 is moved into the casing to the proper extent, then the pipe 113 will be connected to the pressure supply, while the pipe 109 will be connected to the storage reservoir.

The valve rod 114 is connected by a link 130

118 to a control lever 119. This control lever is pivoted at 120 to a rock lever 121, and the rock lever 121 is in turn pivoted to a link 122 which is connected to a cross bar 123. This cross bar in turn is connected to a pin 124 on the piston rod 103 and to a pin 125 on the piston rod 103^a. The other end of the lever 119 is connected by a link 126 to a rock lever 127. This rock lever 127 is connected to a threaded collar 128 on a screw shaft 129 which is capable of being turned by a hand wheel 130.

By turning the hand wheel in the proper direction, the lever 119 can be raised so that the pivotal connection *a* between the lever and the link 126 may be moved to the position indicated at *x*. When the lever is thus raised, it turns about the point 120 as a fixed fulcrum, and this will raise the valve rod and connect the pipe 109 with the oil pressure supply. At the same time, the pipe 113 is connected with the storage reservoir, and this will cause the pistons to move to the left as viewed in Fig. 7, and as the pistons move to the left, they will operate the wedges so as to move the pressure blocks outward. This movement of the pistons to the left, as viewed in Fig. 7, will operate through the rock lever 121 to lower the fulcrum point 120 of the lever 119, the lever now swinging about the point *a* as a fixed fulcrum, and this will move the valve rod down and cut off the oil pressure supply to the cylinders. In other words, the pressure blocks can be moved to the desired extent and held in set position. Furthermore, any giving away of the material thus releasing the pressure blocks so that the pistons will move still further along the cylinders, will, through the compensating device, that is, the cross bar 123 and the parts associated therewith, move the valve rod and thus cause the pistons in the cylinders to be retracted. It is understood, of course, that the vibrations in the machine operating through the system described above may cause slight movements of the valve rod, but the parts will so co-operate and co-act as to accomplish the desired results, and these slight movements in the piston rod will have the advantage of preventing the parts from sticking.

In order to indicate the pressure exerted on the wedges operating the pressure blocks, pipes 131, 131 are provided leading from the cylinders to pressure gauges 132, 132.

In Fig. 9 of the drawings, a modified form of actuating means for the wedges is shown. In this form of the invention, the rod 133 is substituted for the piston rod 103 of the hydraulic control for the wedges. This rod 133 is provided with a threaded portion 134. A threaded collar 135 engages said threaded portion and is located between the bearing blocks 136 and 137 carried by the frame 74 which supports the vertical cutter bar.

There is a ball thrust bearing 138 between the threaded collar 135 and the bearing block 137. The threaded collar 135 is provided with a gear 139. This gear meshes with a pinion 140 which carries a worm gear 141 which in turn meshes with a worm gear 142 carried by a shaft 143 of a motor M³. This motor is independent of the other two motors above described, and may be controlled by hand so as to be operated for the purpose of turning the threaded collar and thus moving the rod 133 endwise. There is, of course, a separate rod for each wedge and a separate actuating threaded collar. The threads on the rod are of such pitch that the wedge will be held in any adjusted position. By operating the motor in one direction, the wedges may be driven forward, or by operating the motor in the opposite direction, the wedges may be withdrawn.

Roof beam recess cutting mechanism

The body portion of the machine is provided with a standard 144. Located in this standard is a vertical shaft 145. The vertical shaft 145 has a splined engagement with a gear 146. The gear 146 meshes with a gear 147 which in turn meshes with a gear 148 mounted on the shaft 51. The shaft 51, as above noted, is operated by a motor M'. Thus it is that the vertical shaft 145 is rotated, and this vertical shaft is capable of endwise movement in the standard 144 without disturbing its connection with the operating mechanism therefor. The standard is provided with an inner sleeve 149, and the shaft 145 is journaled in suitable bearings in this sleeve. Mounted on the upper end of the sleeve is a bracket 150. Journaled in said bracket is a horizontal shaft 151, and the shaft is located adjacent the extreme upper end of the bracket 150. Said shaft 151 is provided with a cutting tool 152. The shaft carries a gear 153. This gear 153 meshes with a gear 154 carried by a stub shaft 155. The stub shaft 155 carries a bevel gear 156 which meshes with a bevel gear 157 on the upper end of the shaft 145. Thus it is that the cutting tool 152 is rotated from the shaft 145. The shaft 151 carrying the cutting tool is capable of endwise reciprocations in the bearings therefor, and the gear 153 is elongated to permit this adjustment of the shaft. Said shaft is moved endwise by a rock lever 158 which is forked at its upper end to engage a collar 159. Intermediate the collar 159 and the gear 153 is a ball thrust bearing 160. The rock shaft is connected by a link 161 to a piston rod 162 which in turn is connected to a piston 163. This piston is mounted in a cylinder 164. Fluid pressure may be admitted to the cylinder for operating on the piston to move the rock lever so as to feed the tool forward into the material. The purpose of this tool is to cut a recess for

a roof beam. The sleeve 149 carrying the tool can be raised and lowered in the standard 144. The tool is brought up to a point adjacent the roof and is then moved through the means described above into the position so as to cut a recess for the roof beam. This standard is located a slight distance in from the vertical cutting bar, but the bracket overhangs the vertical cutting bar so that the tool may be caused to cut a recess in the long vertical wall which is formed by the operation of the machine. This recess is close to the roof, and when a roof beam is placed therein, it can directly engage the roof and support the same. The standard may be lowered after the tool is withdrawn from the recess, and thus the machine moved about, said standard passing under the roof beams which have been placed.

20 The standard is raised by means of a rack 165 which is formed in the side of the sleeve 149, and a pinion 166 carried by a shaft 167 and meshing with said rack. This pinion may be operated by a hand-actuated ratchet mechanism which includes a hand lever 168. When said hand lever turns the shaft 167 in one direction, the sleeve will be raised in the standard, and when turned in the opposite direction, the sleeve will be lowered in the standard.

25 In order to protect the operator of the machine, a roof plate 169 is provided. This roof plate is provided with a suitable opening 170 through which the recess cutter for the roof beam can be raised and lowered.

Operation

30 The operation of the machine is thought to be obvious from the detail description which has been given. The machine is moved about by the caterpillar tractors, and is brought to a proper position for undercutting, sidecutting and removing the material in a mine at one side of a long wall. The horizontal cutter is actuated by a motor carried by the body of the machine, and will cut a horizontal kerf inwardly along the face leading inwardly from the long wall. The vertical cutter bar will cut a vertical kerf which is at the inner end of the horizontal kerf. This vertical cutter bar can be raised and lowered so as to cut a vertical kerf of the proper height. As the vertical kerf is cut, the vertical frame carrying the vertical cutter bar moves into said vertical kerf. The pressure blocks engage the side wall of the vertical kerf and steady and guide the vertical frame and prevent said frame from undue vibration. The pressure pads carried by the frame supporting the vertical cutter bar also bear against the segment plate on the body of the machine well out from the pivotal support of the frame for the vertical cutter bar, and likewise prevent undue vibration in said vertical frame. At the proper time, the pressure blocks are moved

outward through the actuating means therefor, and exert a pressure against the undercut material so as to break it down. As the material breaks down from the cutting or from the pressure blocks, it falls on to the endless conveyors, and will be supported by the steel plates underneath the same. If the amount of material is very heavy, the frame carrying the horizontal cutter will be brought down against the bottom of the horizontal kerf, and thus supported until the material has been removed. The conveyors will convey the material to one side of the machine where it may be delivered on to other conveyors for delivery. The height of the horizontal kerf which is cut by the horizontal cutter, may, of course, be varied by varying the position of the cutting tools. It is essential, however, that it shall be of sufficient depth to receive the horizontal frame with the endless conveyors associated therewith. Likewise, the cutting tools on the vertical cutting frame may be adjusted so as to vary the width of the vertical kerf. It is essential that this kerf shall be wide enough to receive the vertical frame of the mining machine. At proper intervals, the recess cutter is raised to a position adjacent the roof and moved forward so as to cut a recess in the new long side wall which has been formed and a roof beam can be inserted in this recess.

35 It is obvious that minor changes in the details of construction and the arrangement of the parts may be made without departing from the spirit of the invention as set forth in the appended claims.

Having thus described the invention, what we claim as new and desire to secure by Letters-Patent, is—

1. In a longwall mining machine, the combination of a body portion, movable devices for supporting and moving said body portion forward and back, a frame supported by said body portion and projecting from and extending across the entire front end of said body portion and having its lower face disposed in substantially the plane of the lower face of the supporting devices, a vertically disposed shaft carried by said body portion intermediate the sides thereof and adjacent the forward end thereof, means on said body portion for actuating said shaft, an operating sprocket carried by said shaft at the lower end thereof, an endless traveling cutter movable across the front portion of the projecting frame from one side of the body portion to the other side thereof and over said sprocket wheel, and a conveyor disposed adjacent the active portion of the movable cutter and traveling over the upper face of the frame in a direction substantially at right angles to the forward movement of the body portion, and means for adjusting the frame longitudinally of the body portion of the machine for taking up the slack in the traveling

cutter, and means for preventing said frame from lateral movement relative to the body portion of the machine.

- 5 2. In a longwall mining machine, the combination of a body portion, movable devices for supporting and moving said body portion forward and back, a frame carried by said body portion and projecting from and extending across the entire front end of said body portion and having its lower face disposed in substantially the plane of the lower face of the supporting devices, a traveling cutter movable in front of the projecting frame from one side of the body portion to the other side thereof for producing a horizontal kerf to receive the constantly advancing frame, and a conveyor disposed adjacent the active portion of the movable cutter and traveling over the upper face of said frame in a direction substantially at right angles to the forward movement of the body portion for conveying the material received thereon to one side of the body portion and out of the forward path of travel of the machine, said conveyor including a series of connected links having upwardly projecting lugs for engaging and moving the material received thereon.
- 10 3. In a longwall mining machine, the combination of a body portion, movable devices for supporting and moving said body portion forward and back, a frame carried by said body portion and projecting from and extending across the entire front end of said body portion and having its lower face disposed in substantially the plane of the lower face of the supporting devices, a traveling cutter movable in front of the projecting frame from one side of the body portion to the other side thereof for producing a horizontal kerf to receive the constantly advancing frame, and a conveyor disposed adjacent the active portion of the movable cutter and traveling over the upper face of said frame in a direction substantially at right angles to the forward movement of the body portion for conveying the material received thereon to one side of the body portion and out of the forward path of travel of the machine, said conveyor including a series of connected links having upwardly projecting lugs for engaging and moving the material received thereon, said conveyor having a plate extending from side to side thereof and located beneath the portion of the conveyor carrying the material for supporting the conveyor.

- 15 4. In a longwall mining machine, the combination of a body portion, propelling means on which said body portion is mounted for movement forward and back, a frame carried by said body portion and projecting from and extending across the entire front end of said body portion and having its lower face disposed in substantially the plane of the lower face of the propelling means, a

traveling cutter movable across the front portion of said projecting frame from one side of the body portion to the other side thereof for producing a horizontal kerf to receive the constantly advancing frame, a second frame carried by the body portion at one side thereof, a vertically disposed traveling cutter mounted on said second frame for cutting a vertical kerf, and a conveyor independent of the traveling cutter and traveling over the upper face of said first named frame in a direction substantially at right angles to the forward movement of the body portion for conveying the material received thereon to one side of the body portion and out of the forward path of travel of the machine, said second frame being movably connected to the body portion, and manually controlled power means for shifting said second frame.

20 5. In a mining machine, the combination of a body portion, means for supporting and propelling said body portion, a horizontal kerf cutting mechanism carried by said body portion and adapted to be moved into the horizontal kerf beneath the undercut material, a vertically disposed endless cutter chain for cutting a vertical kerf, a frame movably connected to said body portion for supporting said vertically disposed cutter chain, a series of spring pressed cushion pads carried by said frame, and means carried by said body portion against which said pads press for placing the frame under tension and preventing vibrations therein.

25 6. In a mining machine, the combination of a body portion, means for supporting and propelling said body portion, a horizontal kerf cutting mechanism carried by said body portion and adapted to be moved into the horizontal kerf, beneath the undercut material, a vertically disposed endless cutter chain for cutting a vertical kerf, a frame movably connected to said body portion for supporting said vertically disposed cutter chain, a series of spring pressed cushion pads carried by said frame, means carried by said body portion against which said pads press for placing the frame under tension and preventing vibrations therein, and means whereby the tension on each pad may be independently adjusted.

30 7. In a mining machine, the combination of a body portion, means for supporting and propelling said body portion, a horizontal kerf cutting mechanism carried by said body portion, a conveyor carried by said body portion and adapted to be moved into the horizontal kerf beneath the undercut material, a vertically disposed endless cutter chain for cutting a vertical kerf, a frame pivoted to said body portion for supporting said vertical cutter chain, manually controlled power means for shifting said frame, a series of tension pads carried by said frame, and a

segment plate carried by the body portion of the machine against which said pads press for placing said frame under tension and preventing vibrations therein.

5 8. In a longwall mining machine, the combination of a body portion, devices for supporting and moving said body portion forward and back, a motor carried by said body portion for actuating said devices, a frame projecting from and extending across the entire front end of said body portion and having its lower face disposed in substantially the plane of the lower face of the supporting devices, a traveling cutter movable in front of the projecting frame from one side of the body portion to the other side thereof, a motor mounted on said body portion, and devices actuated thereby for operating said cutter, a conveyor independent of the traveling cutter and traveling over the upper face of said frame in a direction substantially at right angles to the forward movement of the body portion, means actuated by said last named motor for operating said conveyor, a vertically disposed frame at one side of said body portion, a movable cutter carried thereby for cutting a vertical kerf, means actuated by said first named motor for operating said movable cutter on the vertical frame, and means actuated by said first named motor for swinging said frame at will.

9. In a longwall mining machine, the combination of a body portion, devices for supporting and moving said body portion forward and back, a motor carried by said body portion for actuating said devices, a frame projecting from and extending across the entire front end of said body portion and having its lower face disposed in substantially the plane of the lower face of the supporting devices, a traveling cutter movable in front of the projecting frame from one side of the body portion to the other side thereof, a motor mounted on said body portion, and devices actuated thereby for operating said cutter, a conveyor traveling over the upper face of said frame in a direction substantially at right angles to the forward movement of the body portion, means actuated by said last named motor for operating said conveyor, a vertically disposed frame at one side of said body portion, a movable cutter carried thereby for cutting a vertical kerf, means actuated by said first named motor for operating said movable cutter on the vertical frame, and means actuated by said first named motor for swinging said frame at will, a cutting device carried by said body portion for cutting a recess for a roof beam, a vertical standard supporting said last named cutting device, means actuated by said second motor for operating said last named cutting device, and manually operated means for raising and lowering said last named cutting device.

10. In a longwall mining machine, the com-

bination of a body portion, movable devices for supporting and moving said body portion forward and back, a frame supported by said body portion and projecting from and extending across the entire front end of said body portion and having its lower face disposed in substantially the plane of the lower face of the supporting devices, a traveling cutter movable in front of the projecting frame from one side of the body portion to the other side thereof for producing a horizontal kerf to receive the constantly advancing frame, and a conveyor independent of the traveling cutter and disposed adjacent the active portion of the movable cutter and traveling over the upper face of said frame in a direction substantially at right angles to the forward movement of the body portion for receiving the material breaking down as it is cut and for conveying the material received thereon to one side of the body portion and out of the forward path of travel of the machine, and means carried by the body portion of the machine for operating said traveling cutter and for operating said conveyor.

11. In a longwall mining machine, the combination of a body portion, movable devices for supporting and moving said body portion forward and back, a frame supported by said body portion and projecting from and extending across the entire front end of said body portion and having its lower face disposed in substantially the plane of the lower face of the supporting devices, a traveling cutter movable in front of the projecting frame from one side of the body portion to the other side thereof for producing a horizontal kerf to receive the constantly advancing frame, and a conveyor independent of the traveling cutter and disposed adjacent the active portion of the movable cutter and traveling over the upper face of said frame in a direction substantially at right angles to the forward movement of the body portion for receiving the material breaking down as it is cut and for conveying the material received thereon to one side of the body portion and out of the forward path of travel of the machine, and means carried by the body portion of the machine for operating said traveling cutter and for operating said conveyor, said frame at the delivery end thereof being inclined upwardly whereby said traveling cutter may pass beneath the frame for engagement with the operating means therefor.

12. In a longwall mining machine, the combination of a body portion, movable devices for supporting and moving said body portion forward and back, a frame supported by said body portion and projecting from and extending across the entire front end of said body portion and having its lower face disposed in substantially the plane of the

lower face of the supporting devices, a vertically disposed shaft carried by said body portion intermediate the sides thereof and adjacent the forward end thereof, means on said body portion for actuating said shaft, an operating sprocket wheel carried by said shaft at the lower end thereof, an endless traveling cutter movable across the front portion of the projecting frame from one side of the body portion to the other side thereof and over said sprocket wheel, and a conveyor independent of the traveling cutter and disposed adjacent the active portion of the movable cutter and traveling over the upper face of the frame in a direction substantially at right angles to the forward movement of the body portion.

13. In a longwall mining machine, the combination of a body portion, caterpillar tractors for supporting and moving said body portion forward and back, a frame carried by said body portion and projecting from and extending across the entire front end of said body portion and having its lower face disposed in substantially the plane of the lower face of the tractors, a driving motor mounted on said body portion for actuating said tractors, a traveling cutter located entirely in front of the tractors and movable across the front portion of the projecting frame from one side of said body portion to the other side thereof for producing a horizontal kerf to receive the constantly advancing frame moved forward by the actuation of the tractors, and a conveyor independent of the traveling cutter and disposed adjacent the active portion of the movable cutter and traveling over the upper face of said frame and in a direction substantially at right angles to the forward movement of the body portion for receiving the material breaking down as it is cut and for conveying the material received thereon to one side of the body portion and out of the forward path of travel of the machine.

14. In a longwall mining machine, the combination of a body portion, propelling means on which said body portion is mounted for movement forward and back, a frame carried by said body portion and projecting from and extending across the entire front end of said body portion and having its lower face disposed in substantially the plane of the lower face of the propelling means, a traveling cutter movable across the front portion of said projecting frame from one side of the body portion to the other side thereof for producing a horizontal kerf to receive the constantly advancing frame, a second frame carried by the body portion at one side thereof, a vertically disposed traveling cutter mounted on said second frame for cutting a vertical kerf, and a conveyor independent of the traveling cutter and disposed adjacent the active portion of the movable cutter and

traveling over the upper face of said first named frame in a direction substantially at right angles to the forward movement of the body portion for receiving the material breaking down as it is cut and for conveying the material received thereon to one side of the body portion and out of the forward path of travel of the machine.

15. In a mining machine, the combination of a body portion, means for supporting and propelling said body portion, an endless vertically disposed cutter bar, a frame pivoted to said body portion and supporting said cutter bar, manually controlled power means for shifting said frame, a plurality of staggered pressure blocks carried by said frame, an actuating wedge associated with each block and movable in the plane of the frame, manually controlled power means for moving said wedges, said blocks being connected to said wedges whereby when the wedges are retracted, the blocks are withdrawn, said manually controlled power means including a cylinder for each wedge, a piston in said cylinder, a piston rod connecting the piston to the wedge, a valve controlled means for supplying hydraulic pressure to said cylinder for moving the pistons, said valve controlled mechanism including a lever connected to the valve intermediate its ends, a rock lever connected to one end of said valve lever and in turn connected to a cross head attached to the pistons so that as the pistons are moved said rock lever will be shifted, and a rock lever connected to the other end of said valve lever and in turn connected to means for manually shifting the position of said last named rock lever.

In testimony whereof, we affix our signatures.

ALEXANDER M. MARION.
EMIL C. GERRY.
